ELECTRIC SWITCH

Alfredo Cianchi, London, England

Application November 5, 1937, Serial No. 173,031
In Great Britain November 7, 1936

12 Claims. (Cl. 200—112)

This invention relates to electric switches comprising a vessel enclosing a plunger which is acted upon by magnetic means to cause it to move and establish or disestablish electrical connection between electrodes passing through the wall of the vessel. Connection may be established or disestablished by means of solid contacts one or both of which is or are moved by the plunger, or by way of mercury or other conducting liquid.

According to the invention the plunger is wholly or partly guided so that it moves clear of the wall of the vessel by one or more guides which extend in the direction of movement of the plunger. I prefer to arrange this guide or these guides in line with the central axis of movement of the plunger although a similar result may be obtained if it or they is or are offset from its axis. The invention may include further features which are hereinafter referred to and claimed.

It will now be described with reference to the accompanying diagrammatic drawing which illustrates by way of example a number of switches embodying it. In the drawing

Figures 1 to 4 are longitudinal sectional views of four mercury switches provided with different forms of plunger guide.

Figure 5 is a perspective view of a modified form of guide.

Figures 6 and 7 are longitudinal sectional views of another form of mercury switch and of a solid-contact switch respectively provided with a plunger guide according to the invention.

In all the figures of the drawing except Figure 5, 1 is the vessel of the switch, 2 and 3 are the electrodes which pass through its wall in which they are fused, 4 is the plunger and 6 the electromagnetic means operating it. The switches of Figures 1 to 4 are mercury switches, the plunger in each case consisting of a tubular member 4 of glass, quartz, porcelain, steatite, or other spark-resisting material which is provided at its upper end with a magnetic armature 5 in the form of a length of iron tube fitting closely on the outside of the tubular plunger near the top. The plunger has a closed lower end forming a cup containing a quantity of mercury 7 and the plunger 4 with the mercury 7 in it normally floats on a main body of mercury 8 in the lower part of the switch vessel 1. The upper electrode 2 passes down the inside of the tubular plunger 4 and coaxially with it and dips into the pool of mercury 7. The lower electrode 3 projects into the body of mercury 8 in which it is

continuously immersed. At a point displaced from its lower end the plunger has an opening 9 so that when the plunger is drawn down in the mercury 8 on energising of the solenoid 6, mercury from 8 passes through the opening 9 into the pool 7 so as to establish electrical connection between the electrodes 2 and 3. When the solenoid is de-energised the plunger 4 rises due to its buoyancy and the two bodies of mercury are separated at the opening 9 so as to disestablish electrical connection between the electrodes 2 and 3. In the switch of Figure 1 the plunger 4 is guided solely on the upper electrode 2 which passes through two spaced constrictions on the plunger 4. The upper constriction is formed by turning in the upper end of the tube, for example after fusing it, and as indicated at 10. The second constriction is formed by making a neck 11 in the plunger 4 at a point displaced sufficiently far from 10 to ensure that the plunger 4 is adequately guided by the electrode 2 so that it moves freely up and down in the direction of its longitudinal axis without touching the wall of the vessel 1. Although the constrictions are described as being formed by deforming parts of the plunger 4, it is to be understood that when the term "constriction" is employed, it is intended to cover also the insertion in the plunger of separate members having apertures substantially fitting the electrode. Openings are provided to enable mercury which may have got into the plunger above the lower constriction to escape easily.

In the switch of Figure 2 the upper end of the plunger is guided on the electrode 2 by a constriction 10 in a similar way to that adopted in the switch of Figure 1. The lower end of the plunger, however, is provided with a coaxial projection 12 which passes into an opening or eye on a member 13 secured to the upper end of the lower electrode 3. Here again the guides 2 and 12 guide the plunger 4 and armature 5 so that they move up and down without touching the walls of the vessel. Naturally the eye could be on the end of a member mounted on the plunger as by being fused into it instead of on the electrode and the electrode arranged to enter the eye; or the electrode could pass directly into a coaxial opening in the plunger.

In the switch of Figure 3 the lower end of the plunger is guided in the same way that the lower end of the plunger of Figure 2 is guided, but the upper end is guided by projections 14 on the plunger itself. The upper edge of the plunger is shown as being turned outwards for this purpose

and a continuous ring formed in this way or otherwise may be employed, but it is preferred to interrupt the ring so that the plunger engages with the wall at a number of separate 5 points disposed around its axis and preferably three. The projections could be formed on a separate member fitted to the plunger or formed by bending outwards parts of the armature 5.

The switch of Figure 4 is similar to the switch 10 of Figure 2 except that the guide 12, instead of passing through a member 13 carried on the end of the electrode 3, passes through a member 13 carried on the switch vessel 1 from the wall of which it is spaced by radial arms so as to 15 allow free passage of mercury to the electrode 3.

Instead of using a lower guide such as that of Figure 2, the lower end of the electrode 1 could be provided with an enlargement or a spider or other projection engaging the inner wall of the 20 tubular plunger near the bottom, the inner wall then being made parallel-sided at least for a length corresponding to the distance through which the plunger moves. The lower part of such an electrode is illustrated in perspective in 25 Figure 5, the lower end in this case being provided with a three-armed plunger, the end surfaces of which come into contact with the inner wall of the plunger to guide it. If desired, of course, two spaced spiders or other enlargements or projections 30 could be provided on the electrode to engage the inner wall of the plunger at two spaced points. It would not then be necessary to provide any other guide for the plunger.

Figure 6 illustrates a form of mercury switch 35 which differs from that of Figures 1 to 4. The switch of Figure 6 is similar to the ordinary type of plunger mercury switch in which contact is made or broken merely by displacing the level of a body of mercury as a result of varying the 40 extent of immersion in it of a plunger in the form of an open-ended tube. Such a plunger could be employed in the present case and be guided by an upper electrode 2 provided with spaced spiders such as those illustrated in Figure 5. In the switch of Figure 6, however, the plunger is in the form of a length of glass or like tube, the two ends of which are turned inwards to form two constrictions which slide up and down on the upper electrode 2. The plunger is 45 provided with an armature 5 in a similar way to the plungers of Figures 1 to 4. The electrode 3 of the switch of Figure 6 is in a side limb of the main switch vessel into which mercury flows to establish connection between the electrodes 50 2 and 3 when the plunger is drawn down to raise the level of mercury.

The switch of Figure 7 is a switch in which connection is made and broken between solid contacts. The contacts are indicated at 55 and 16, 60 both being spring contacts connected respectively to the electrodes 2 and 3. Contact 15 is fixed while the contact 16 is mounted on the plunger 4 which is moved by magnetic means by way of an armature 5 as in the case of the other switches 65 described above. The plunger 4 is normally pulled in such a direction that the contacts 15 and 16 are separated but is moved against the action of the spring 17 to cause the contacts to interengage and establish connection between 70 the electrodes 2 and 3 when the solenoid is energised. As soon as it is de-energised the spring pulls the plunger back to disengage the contacts. The plunger is guided on the electrode 2 in one of the ways described above so that it moves 75 clear of the walls of the vessel 1.

It will be understood that in all cases the area of contact between the plunger 4 and the guide or guides is made as small as is reasonably possible so as to enable the plunger to move freely.

In the case of the mercury switches described above it will be noticed that the clearance between the armature 5 and the wall of the vessel 1 is less than that between the lower part of the plunger where it enters the mercury. It is, of course, desirable for the armature to be as near 10 the wall as possible for magnetic reasons, but if the plunger were made only the same distance from the wall of the vessel, difficulty would be experienced with the mercury which would not then be likely to rise and fall freely or else undue 15 friction would be caused. If necessary the lower part of the plunger may be made of smaller diameter than the upper part so as to obtain a still greater clearance at the part where it is immersed in the mercury. The part of the plunger 20 that enters the mercury is also made smooth and of a tapered, rounded or other shape that offers a low resistance to movement of the plunger in the mercury, and for the same reason projections of substantial area on the part of the plunger 25 that enters the mercury are avoided. Thus, in the arrangement of Figure 3, although projections 14 are employed they are employed on the part of the plunger that does not enter the mercury. By employing guiding means according to 30 the invention, and possibly also one or other of the expedients just described, it is possible to make a switch which will operate with a low consumption of current if it is operated electromagnetically. The switch could, however, if desired 35 be a movable magnet in which case the energy required to move the magnet would be correspondingly low.

I claim:

1. An electric switch comprising a vessel containing a body of conducting liquid, a movable plunger in said vessel containing a conducting liquid, an electrode passing through the wall of the vessel into said first body of conducting liquid, a second electrode passing through the 40 wall of the vessel into said second body of conducting liquid, magnetic means for actuating said plunger to vary the extent of immersion thereof in said first body of conducting liquid selectively to establish and break electrical contact between 45 said electrodes, and a plurality of guiding means disposed at points spaced longitudinally in the direction of movement of said plunger within said vessel for guiding said plunger clear of the wall of said vessel, with at least one of said guiding 50 means associated with said vessel and extending in the direction of movement of said plunger.

2. An electric switch comprising a vessel containing a body of conducting liquid, a movable plunger in said vessel containing a conducting liquid, an electrode passing through the wall of the vessel into said first body of conducting liquid, a second electrode passing through the 60 wall of the vessel into said second body of conducting liquid, magnetic means for actuating said plunger to vary the extent of immersion thereof in said first body of conducting liquid selectively to establish and break electrical contact between 65 said electrodes, and a plurality of guiding means disposed at points spaced longitudinally in the direction of movement of said plunger within said vessel for guiding said plunger clear of the wall of said vessel, with at least one of said guiding 70 means mounted on said vessel and extending in the direction of movement of said plunger.

3. An electric switch comprising a vessel containing a body of conducting liquid, a movable plunger in said vessel containing a conducting liquid, an electrode passing through the wall of the vessel into said first body of conducting liquid, a second electrode passing through the wall of the vessel into said second body of conducting liquid, magnetic means for actuating said plunger to vary the extent of immersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with at least one of said guiding means mounted on said plunger and extending in the direction of movement thereof and cooperating with a guide member on said vessel.
4. An electric switch comprising a vessel containing a body of conducting liquid, a movable plunger in said vessel containing a conducting liquid, an electrode passing through the wall of the vessel into said first body of conducting liquid, a second electrode passing through the wall of the vessel into said second body of conducting liquid, magnetic means for actuating said plunger to vary the extent of immersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with one of said guiding means mounted on said vessel and extending in the direction of movement of said plunger and the other of said guiding means being formed on said plunger extending in the direction of movement thereof and cooperating with a guide member on said vessel.
5. An electric switch comprising a vessel containing a body of conducting liquid, a tubular plunger in said vessel containing a conducting liquid and movable in the direction of its longitudinal axis, an electrode passing through the wall of the vessel into said first body of conducting liquid, a second electrode passing through the wall of the vessel into said second body of conducting liquid, magnetic means for actuating said plunger to vary the extent of immersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with at least one of said guiding means comprising a guide member mounted on said plunger and provided with lateral projections engaging the inner wall of said vessel above the level of the bodies of conducting liquid therein.
6. An electric switch comprising a vessel containing a body of conducting liquid, a tubular plunger in said vessel containing a conducting liquid and movable in the direction of its longitudinal axis, an electrode passing through the wall of the vessel into said first body of conducting liquid, a second electrode passing through the wall of the vessel into said second body of conducting liquid, magnetic means for actuating said plunger to vary the extent of immersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with at least one of said guiding means comprising a guide member mounted on said plunger and provided with lateral projections engaging the inner wall of said vessel above the level of the bodies of conducting liquid therein.
7. An electric switch comprising a vessel containing a body of conducting liquid, a tubular plunger in said vessel containing a conducting liquid and movable in the direction of its longitudinal axis, an electrode passing through the wall of the vessel into said first body of conducting liquid, a second electrode passing through the wall of the vessel into said second body of conducting liquid, magnetic means for actuating said plunger to vary the extent of immersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with at least one of said guiding means comprising a guide member mounted on said plunger and provided with lateral projections engaging the inner wall of said vessel above the level of the bodies of conducting liquid therein.
8. An electric switch comprising a vessel containing a body of conducting liquid, a tubular plunger in said vessel containing a conducting liquid and movable in the direction of its longitudinal axis, an electrode passing through the wall of the vessel into said first body of conducting liquid, a second electrode passing through the wall of the vessel into said second body of conducting liquid, magnetic means for actuating said plunger to vary the extent of immersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with at least one of said guiding means comprising a guide member mounted on said plunger and provided with lateral projections engaging the inner wall of said vessel above the level of the bodies of conducting liquid therein.
9. An electric switch according to claim 1, wherein at least one of the electrodes forms a part of the guiding means.
10. An electric switch according to claim 5, wherein one of said electrodes constitutes said guide member.
11. An electric switch comprising a vessel containing a body of conducting liquid, a tubular plunger in said vessel containing a conducting liquid and movable in the direction of its longitudinal axis, an aramture of magnetic material mounted on the upper end of said plunger, an electrode passing through the wall of the vessel into said first body of conducting liquid, a second electrode passing through the wall of the vessel into said second body of conducting liquid, magnetic means cooperating with said armature for actuating said plunger to vary the extent of im-

5 mersion thereof in said first body of conducting liquid selectively to establish and break electrical contact between said electrodes, and a plurality of guiding means disposed at points spaced longitudinally in the direction of movement of said plunger within said vessel for guiding said plunger clear of the wall of said vessel, with at least one 10 of said guiding means associated with said vessel and extending in the direction of movement of said plunger, said armature being spaced from the wall of the switch vessel but disposed closer thereto than the lower part of said plunger which enters said first body of conducting liquid, the space between the latter and said wall being made 15 large enough to avoid the setting up of undue resistance to movement of said plunger.

10 12. An electric switch comprising a vessel containing a body of conducting liquid, a tubular plunger in said vessel containing a conducting liquid and movable in the direction of its longitudinal axis, said plunger having an opening near the lower end thereof, an electrode passing through the wall of the vessel into said first body of conducting liquid, a second electrode passing

5 through the wall of the vessel into said second body of conducting liquid, magnetic means for actuating said plunger to vary the extent of immersion in said first body of conducting liquid selectively to establish and break electrical contact between said electrodes by the emergence and separation of said bodies of conducting liquid, respectively, at said opening, and a plurality of guiding means disposed at points spaced longitudinally in the direction of movement of said plunger within said vessel for guiding said plunger clear of the wall of said vessel, said guiding means comprising said second electrode extending into said plunger and dipping into said conducting liquid therein, and at least one constriction 10 formed on said plunger adapted to slide on said last-mentioned electrode as the plunger moves, said one or more constrictions being so disposed that they do not slide on to the part of the electrode which lies opposite said opening 15 when the plunger is in the position in which electrical contact is broken.

ALFREDO CIANCHI.
